CLAIM

I claim the ornamental design for a nestable specimen collection cup, as shown and described.

DESCRIPTION

FIG. 1 is a perspective view of a nestable specimen collection cup showing my new design;

FIG. 2 is a second perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof; and,

FIG. 8 is a rear elevation view thereof.

1 Claim, 4 Drawing Sheets
